CLAIM

The ornamental design for a display screen with animated graphical user interface for video player, as shown and described.

DESCRIPTION

FIG. 1 is a front view of the first image in a sequence for a display screen with animated graphical user interface for video player;

FIG. 2 is a front view of the second image;

FIG. 3 is a front view of the third image;

FIG. 4 is a front view of the fourth image;

FIG. 5 is a front view of the fifth image;

FIG. 6 is a front view of the sixth image;

FIG. 7 is a front view of the seventh image;

FIG. 8 is a front view of the eighth image;

FIG. 9 is a front view of the ninth image; and,

FIG. 10 is a front view of the tenth image.

The speckled shading shown in the lower portion of the display screen shows a visual contrast in appearance and forms part of the claimed design.

1 Claim, 10 Drawing Sheets
